UNITED STATES PATENT OFFICE

2,566,543

TAPPET ADJUSTING TOOL

Edward Weglarz, Cicero, Ill.

Application February 4, 1948, Serial No. 6,122

4 Claims. (Cl. 81—3)

1 The main objects of this invention are, to provide an improved tool for adjusting and setting lock-nut machine screws; to provide an improved tool of this kind having a nut socket and screw driver co-axially arranged and relatively shiftable axially of each other to permit the tool to be placed upon a machine screw with a lock nut to successively adjust said screw and nut; to provide improved means for releasably holding nut sockets of differing sizes in co-axial adjustable relationship with said screw driver; to provide an improved arrangement of resilient means for determining the normal axial relationship of said nut socket and screw driver and permitting relative axial shifting thereof whereby said tool may be used for separately adjusting either the lock nut or the machine screw; to provide an improved tool construction of this kind which permits the tool to be operated by one hand so as to free the other hand for operations correlative to the effective adjustment of an associated machine screw and lock nut; and to provide a tool of this kind which is simple and economical to manufacture and facile and efficient to use.

In the drawings:

Fig. 1 is a perspective, exploded view of a preferred form of tool of this kind showing the nut-socket separated from the spring clip which operatively supports it on the tool shank;

Fig. 2 is a side elevation, partly sectional, of the improved tool in place on a machine screw and lock nut, the parts being shown in their relative positions which permit a turning of the lock nut on the screw;

Fig. 3 is a view similar to that shown in Fig. 2 but with the tool shank depressed and slightly turned so as to bring the screw driver tip of the shank into registration with the kerf in the end of the screw; and

Figs. 4, 5, and 6 are transverse, sectional details taken on the lines 4—4, 5—5, and 6—6, respectively, of Fig. 3.

The preferred form of tool, embodying this invention, comprises a shank 7 which has its end formed as a screw-driver tip 8 and which mounts a chuck or spring clip 9 for releasably holding a nut-socket 10 in operative association with said screw-driver tip 8, a compression spring 11, interposed between the clip 9 and a handle 12, serving to determine the operative relationship of said screw-driver tip 8 and said nut-socket 10 with respect to a machine screw 13 and its lock nut 14.

The shank 7 is of circular cross-section throughout almost its entire length except for a short distance above the screw-driver tip 8 where it is of rectangular cross-section 15. The juncture of the circular and square parts of the shank 7 forms a shoulder 16 which limits the downward movement of the clip 9 under the

influence of the spring 11. The screw driver tip 8 is of conventional form. The upper end of the shank is received in a bore 18 formed in a medial knob 17 on the handle 12 and anchored to the handle by a set screw 19.

The screw-driver tip 8 is positioned so that its greater dimension is in the plane of the handle 12. This enables the operator to determine the disposition of the screw-driver tip 8 by the position of the handle 12.

15 The nut-socket supporting-clip or chuck 9 is in the form of a disk. Preferably it is spring metal and has at least three radially-disposed fingers or prongs 20 which are adapted to yieldingly grip and hold the nut socket 10 in operative position on the squared end 15 of the shank 7. The disk 9 is provided with a central circular hole or aperture 21 which permits the clip to slide on the circular part of the shank 7.

20 The diametrical size of the nut-socket supporting clip 9 depends upon the size of nut sockets 10 with which the tool is to be used. Clips of varying diameters—especially between the fingers 20—can be provided for use in supporting differing size nut sockets 10 on the shank 7. Being made of spring material and the fingers 20 being slightly curved, as most clearly shown in Figs. 2 and 3, a clip 9 of a given diameter is capable of supporting nut sockets 10 of at least two differing sizes.

25 The nut socket 10 is a more or less conventional tool accessory, purchasable on the open market. Such nut sockets are usually of cylindrical form and have one end formed with a hexagonal-shaped bore 22 and the other end formed with a squared bore 23. The hexagonal bore 22 is of a standard size to permit the socket to fit over and operatively engage a standard size nut 14. The square bore 23 permits the insertion 30 of a squared-end tool whereby the socket 10 may be turned for tightening or loosening the nut 14 on the screw 13.

35 The socket 10 is gripped by the clip fingers 20 and slidably held on the squared part 15 of the shank 7. The length of the socket is such that when the clip 9 is forced by the spring 11 into its lowermost position against the shank shoulder 16 the open end of the hexagonal bore 22 extends well below the screw-driver tip 8 on the shank 7 and fits over the nut 14 with the screw-driver tip 8 out of contact with the screw 13 so long as no pressure is applied to force the shank down against the action of the spring 11.

40 The spring 11 is of such a character as will retain the clip 9 against the shank shoulder 16 so long as no material pressure is consciously applied by the operator on the handle 12.

45 The handle 12, as herein shown, is a single piece of metal with an integral medial knob 17 bored to receive the shank 7, whereby the parts

are secured together, as hereinbefore explained.

The screw 13 and nut 14, for use with which this tool has been especially designed, constitutes standard parts of a tappet 24. Generally close adjusting of the screw 13 is required in order to secure the proper action between the tappet 24 and a reciprocating element 25.

Very frequently this lock-nut and screw adjustment is located in a place of difficult accessibility and which precludes the possibility of being easily reached, especially with both hands. Moreover, when the screw 13 is adjusted it is necessary to use one hand to hold a gauge between the screw head and the element 25 to determine proper spacing. Accordingly, to be able to secure a proper adjustment of a screw 13 and nut 14 it is imperative to have a readily-insertable, easily-operable, single-handed tool which can be used for first loosening the nut 14, adjusting the screw 13, and then tightening the nut, without having to remove the tool after it has been placed in position.

A tool of the construction herein shown possesses these imperative qualities. With one hand grasping the handle 12, the operator may insert the shank in between other parts of the machinery and place the bore 22 of the socket 10 into engagement with the nut 14. So long as no material pressure is applied on the handle 12, to compress the spring 11, the screw-driver tip 8 will remain out of contact with the screw 13. In such case the turning of the handle 12 results in a turning of the nut 14. Once the nut 14 is loosened a depression on the handle 12—often accompanied by a slight turning of the shank 7—will bring the screw-driver tip 8 into contact with the kerf 26 in the screw 13. Thereupon, a further turning of the handle 12 will permit the desired adjustment of the screw 13. Once the screw 13 has been properly adjusted with regard to the element 25, the pressure on the spring 11 may be relaxed, which will cause the screw driver tip 8 to recede from the screw kerf 26, permitting the operator to again rotate the shank so as to tighten the nut 14 and lock the screw 13 against displacement.

Variations and modifications in the details of structure and arrangement of the parts may be resorted to within the spirit and coverage of the appended claims.

I claim:

1. A tool for use in adjusting an associated machine screw and lock nut comprising, a circular shank having a non-circular end terminating in a screw-driver tip and forming a shoulder at the juncture of said circular and non-circular portions of said shank, a disk having a circular opening therein whereby said disk is slidably mounted on said shank inwardly of said shoulder, axially-disposed prongs formed on said disk and adapted to releasably engage and hold therein a nut socket having a non-circular opening adapted to engage the non-circular end of said shank whereby said socket is rotatable with said shank, and a compression spring embracing the circular part of said shank and normally urging said disk into engagement with said shoulder to hold said socket with the nut-engaging part thereof beyond said screw-driver tip in position to operatively engage said lock nut but permitting said socket to be retracted along said shank to enable said screw-driver tip to engage a kerf on said machine screw.

2. A tool for use in adjusting an associated machine screw and lock nut comprising, a cir-

cular shank having a non-circular end terminating in a screw-driver tip and forming a shoulder at the juncture of said circular and non-circular portions of said shank, a transverse handle secured to the upper end of said shank, a spring disk having a circular opening whereby said disk is slidably mounted on said shank inwardly of said shoulder, said disk having radially-extending resilient prongs adapted to releasably engage and hold a nut socket therein with the nut-receiving part thereof extending beyond said screw-driver tip, and a compression spring embracing the circular part of said shank intermediate said shoulder and handle and normally urging said disk into engagement with said shoulder to hold said socket with the nut-engaging part thereof beyond said screw-driver tip in position to operatively engage with said lock nut but permitting said socket to be retracted along said shank to enable said screw-driver tip to engage a kerf on said machine screw.

3. A tool for use in adjusting an associated machine screw and lock-nut comprising a shank having at one end a non-circular enlargement, which is insertable into an axial non-circular opening in a nut-socket to connect said socket and shank together for conjoint rotation and is slidable through said opening to break said connection whereby said socket is independently rotatable on said shank, said enlargement terminating in a screw driver tip, means carried by said shank for detachably holding said nut-socket, and a compression spring carried by said shank normally urging said socket toward said tip to hold said enlargement within said opening, said means being slidable along said shank away from said tip to disconnect said enlargement from said opening whereby said screw driver tip may be rotated independently of said nut-socket.

4. A tool for use in adjusting an associated machine screw and lock-nut comprising a circular shank having at one end a non-circular enlargement which is insertable into a non-circular opening in a nut-socket to connect said socket and shank together for conjoint rotation and is slidable through said opening to break said connection whereby said socket is independently rotatable on said shank, said enlargement terminating in a screw driver tip, a chuck rotatably carried by said shank and slidable therealong for detachably holding said nut-socket, and a compression spring carried by said shank normally urging said chuck toward said tip to position said enlargement within said opening, said chuck being slidable along said shank away from said tip to disconnect said enlargement from said opening whereby said screw driver tip may be rotated independently of said nut-socket.

EDWARD WEGLARZ.
